UNITED STATES PATENT OFFICE.

JAMES H. COFFMAN, OF COLUMBUS, OHIO, ASSIGNOR TO THE WISCONSIN CHAIR COMPANY, OF PORT WASHINGTON, WISCONSIN.

DESIGN FOR A CHAIR BACK AND SEAT.

SPECIFICATION forming part of Design No. 32,237, dated February 13, 1900.

Application filed January 4, 1900. Serial No. 399. Term of patent 7 years.

To all whom it may concern:

Be it known that I, JAMES H. COFFMAN, a citizen of the United States, residing at Columbus, in the county of Franklin, in the State of Ohio, have invented and produced a new and original Design for a Chair Back and Seat, of which the following is a specification, reference being had to the accompanying drawings, showing a part thereof.

10 In said drawings, Figure 1 is a front elevation of a chair back and seat, showing my design. Fig. 2 is a longitudinal vertical section of the same, taken on line $a-a$ in Fig. 1. Fig. 3 is a top plan view of the same, these three views being deemed necessary to fully illustrate my design.

The feature of my design for chair backs and seats consists in the peculiar surface formation of the same.

20 My design relates to a bent-wood chair back and seat and may be described as follows:

The seat proper, or that portion of the design between the front edge $b-b$ and the points $c-c$ in cross-section at the center, takes the 25 form of an irregular compound curve, curving up and over from the front edge to the point 3, and from the point 3 downward to the point 4, and from point 4 to the point 2, forming the deepest part of the curve. All of

the portion between the front edge and the 30 points $c-c$ will be straight across from side to side on its surface. At the point 2, or, more properly speaking, on a line taken between the points $c-c$, or where the seat proper stops and the back portion begins, the curve ends, 35 and from 2 my design in cross-section extends to its top or to the point 5 in the top edge on a straight line.

The upper edge of my design, between the two points $d-d$ and $d-d$ of the side edges, takes the 40 form of a portion of the radius of a large circle, and the whole portion of my design, between the points $d-d$ and the points $c-c$, curves outward from the center line toward the side edges. This whole curved surface will follow 45 substantially the curve of the line between the points d and d .

Having thus described my design, what I claim is—

The design for a chair back and seat substantially as shown and described.

Signed by me at Cleveland, Ohio, this 3d day of October, 1899.

JAMES H. COFFMAN.
